ALBERT EDWARD CLEGG, OF LEEDS, ENGLAND.

GLASS-BOTTLE-MAKING MACHINE.

1,132,071.

Specification of Letters Patent. Patented Mar. 16, 1915.

Application filed October 18, 1912. Serial No. 726,468.

To all whom it may concern:

Be it known that I, ALBERT EDWARD CLEGG, a subject of the King of Great Britain and Ireland, residing at Leeds, in the county of York, England, have invented certain new and useful Improvements in Glass-Bottle-Making Machines, of which the following is a specification.

This invention relates to machines of the turnover type for making and blowing bottles by means of compressed air, in which the outside of the bottle mouth or ring, as it is termed, is formed in a divided ring mold, used in conjunction with, but separate from either, the gathering or parison mold or the finishing mold; while a hollow nipple forms the interior of the mouth or neck, and a piercing rod or plunger passing through a central hole in the nipple pierces the metal, *i.e.* the glass of the neck; air being admitted to the hole thus formed in the metal for blowing the bottle in the finishing mold. Such a machine for example is described in the specification of British Letters Patent No. 27,971 of 1904.

One of the chief objects of my invention is to permit a bottle thus manufactured to have the name of the brewer or manufacturer of the ale or any other contents, or any other words of advertisement molded in the front of a bottle having a stopper held by a pivoted wire bail, without interference of the fin formed by the sections of the body-mold, the front being that face of the bottle, on which the wire bail is turned down in removing the stopper from the neck, and which, therefore, is naturally presented toward the person opening the bottle. This is effected by combining with a body-mold in two sections, arranged with the plane of division at right angles to the face of the machine, so that said sections open laterally in opposite directions, a ring-mold for forming the neck of the bottle, consisting of a pair of sections having projections in the middle parts of their inner faces adapted to form in the exterior of the neck of the bottle a pair of indentations which serve for pivoting the ends of the stopper-locking wire bail, the plane of division of the ring-mold sections being consequently parallel to the front of the machine and at right angles to the plane of division of the body-mold. Thus constructed, the ring-mold sections open respectively forward or backward, in other words away

from or toward the machine; and the indentations are arranged to let the wire bail fold down on the smooth face of the body of the bottle corresponding to one of the body-mold sections, which face of course has no fin in it and may well have words impressed therein by the operation of molding; this face, as stated, constituting in use the natural front of the bottle, though when first produced it is presented at right angles to the front of the machine. The term body-mold, as here used, applies both to the parison mold and the finishing mold, since both have their sections arranged in the same way.

I attain these objects by the mechanisms illustrated by the accompanying drawings, in which—

Figure 1 is a front elevation of the ring opening and closing mechanism and the neck piercing mechanism, which are carried by the turnover brackets of the glass blowing machine. Fig. 2 is a horizontal section, looking downward on line A A of Fig. 1 and Fig. 3 is a side elevation. Fig. 4 is a front-to-back mid section of the lower part of Fig. 1. Fig. 5 is a modification of Fig. 4 for the purpose hereinafter set forth. Fig. 6 is a side elevation of the means for piercing the metal of the neck while in the gathering mold.

The same reference letter or figure is used for the same part in all the views.

a a are the bearings for the levers carrying the parison mold formed at the ends of a cross plate *b* forming part of the turnover bracket.

c c¹ are the two halves of the ring mold for shaping the outside of the bottle neck, carried respectively by the two arms *d d¹*, these latter being fixed to the lower ends of the pivot shafts *e e¹*. The shafts *e e¹* are fitted rotatably in the pillars *f f¹*, which are cast on the upper side of the plate *g*, the latter forming part of the turnover frame or bracket. The shafts *e e¹* are partially rotated in unison, so as to move the two arms *d d¹* toward each other, to close the halves of the ring mold together, and from each other to open apart the two halves of the ring mold by means of the operating lever *h*. The connections consist of the two arms *i i¹* fixed to the upper ends of the shafts *e e¹*, and the connecting link *j* joining the two arms *i i¹* together, and the connecting link *k* joining the end of the

arm i^2 with a pin l fixed to the operating lever h . The opening movement is effected by moving the lever in the direction indicated by the arrow in Fig. 2, and the closing movement is effected by the spring p .

5 In the case of indent ring molds, that is provided with projections c^2 for forming diametrically opposite indents in the outside of the bottle ring, as shown in Fig. 5 to receive the ends of wire fasteners for holding the stoppers of the bottle, the plane of the division of the ring mold is made at right angles to the plane of division of the parison and finishing molds, which open to the right and left when viewed from the front. The 10 projections for forming the indents are on a line transverse to the plane of division of the ring-mold.

The plane of division of the finishing mold for the bottle-body, as also of the parison mold for the same, is at right angles to the front of the machine; but the plane of division of the ring-mold for forming the bottle-neck is parallel to the front 15 of the machine; so that the body-mold opens laterally and the fin formed in the bottle-body by this mold will be at right angles to the front of the machine with a smooth rounded finless face at the side for the front 20 of the bottle; but the ring-mold sections open respectively forward away from the machine and rearward toward the machine. The movement of the rearward ring-mold section, though sufficient, is limited by the 25 bracket plate carrying the mechanism from the swiveling head, but in order to move the front section of the ring-mold out of the way of the bottle when the finishing mold is swung to one side it is necessary to give 30 a greater swing to the arm carrying this latter section than to the arm carrying the rear section. Consequently the lever i^2 operating arm d , which carries the said front section of the ring-mold, is made one half 35 as long as lever i , which similarly actuates arm d^2 carrying the rear section of said mold, that the former arm and section may be swung well to one side, facilitating the removal of the molded bottle. These arms 40 are pivoted at opposite sides of the central vertical plane, passing through the said ring-mold sections. The hereinbefore mentioned indent-forming projections are in 45 this plane.

50 This arrangement of the said projections with relation to the lines of division of the body-mold as hereinbefore described, insures that the wire bail for fastening the stopper will be turned down in opening the 55 same on a part of the bottle-body free from any fin, which may therefore receive a molded name or any desired words and will constitute the front of the bottle, being naturally presented to a person as he opens 60 the latter. The important feature of this

construction is the location of the indents in a plane corresponding to the plane of division of the body-mold so that the wire bail may fold down, in opening the latter, on a smooth front without any fin and not 70

on the fin formed by the body-mold sections, as the latter fin would prevent the proper molding of the desired words. This is an important improvement for it makes the opening of the bottle, and every presentation or arrangement of it in position to be 75 opened, an advertisement of the contents or such other announcement as may be desired.

m shown in dotted lines in Fig. 1, and in section in Fig. 4, is a central hollow pillar, 80 cast on the upper side of the plate n , which is bolted to the plate g , the pillar m being situated midway between the side pillars f and f^1 .

o is the outer sleeve fitting rotatably on 85 the pillar m , and having the operating lever h cast on it.

q is the so-called adjusting sleeve, fitting inside the pillar m , its upper part projecting above the pillar m , being formed with 90 two collars r which form a circumferential runner race. The sleeve s , carrying the nipple u at its lower end, is screw-threaded on the outside toward its upper end, so as to fit the internal screw formed at the 95 upper end of the adjusting sleeve q . By rotating the sleeve q , the inner sleeve may be raised or lowered to adjust the position of the nipple, the locking nut t being tightened when the adjustment has been made. The 100 interior of the sleeve s is connected by the inlet opening w with the compressed air pipe. The piercing rod or plunger v passes into and through the nipple u and through a packing gland, fitted in the screw-threaded socket hole x in the upper end of the sleeve s .

6, Figs. 2 and 3 is an inclined cam, which projects as a rib from the rear side of the sleeve o .

7 is a forked lever, hinged at 8 to the turn-over frame or bracket, and carrying the antifriction roller 9 on its under side, the latter resting on the upper or working side of the cam 6.

Runners 10 carried at the ends of the fork arms of the lever 7, engage in the groove or race between the collars r on the adjusting sleeve q , so that the movement of the operating lever h to open the ring mold c^2 , 120 by means of the above described mechanism, raises the sleeves q and s , so that the nipple u is clear off the ring mold i , *i.e.* clear of the bottle neck. Thus the latter is not broken off or damaged, when the hinged bracket 125 carrying the finishing mold is swung to one side. The two halves of the ring mold, when opened apart, are clear of the path of the bottle neck during the swinging of the finishing mold to one side. The downward 130

- movement of the nipple u and of the forked lever 7 is effected by the spring 5. It will be evident that the opening of the ring mold c c^1 and the raising of the nipple u 5 are thus effected simultaneously by the movement of the lever h by hand, while the closing of the ring mold and the lowering of the nipple take place simultaneously under the action of the springs 5 and p .
- 10 In case it is desired to admit the air for blowing the bottle over the full width of the bottle mouth, the construction illustrated by and described with reference to Fig. 4 is modified as follows, and as illustrated by 15 Fig. 5.
- An intermediate sleeve q^1 is inserted between the sleeves q and s , being fitted vertically slidably in the sleeve q , and connected by screw threads to the upper part of the 20 nipple carrying sleeve s , so that in this case the intermediate sleeve q^1 becomes the adjusting sleeve. The nipple u passes through an opening in the ring u^1 screwed into the lower end of the sleeve q , the underside of the 25 ring being indented, forming an annular groove or trough u^2 , which is adapted, on inversion of the mechanism, to receive molten glass, to obtain a glass joint for preventing leakage of air. The lower half of 30 the intermediate sleeve is widened out to allow the air to pass through the holes s^2 in the sleeve s , down into the space between the nipple and the sleeve q . The sleeve q is raised as before by the cam 6 and lever 7, so 35 that the indented ring u^1 is lifted clear off the top of the bottle ring, as the ring mold is opened; while the sleeves q^1 and s are raised by a hinged forked lever 7^a , and link 14 attached to the lever 15 fixed to the spigot 40 or spindle of the tap for admitting compressed air, which then passes around the outside of the raised nipple and through the large opening in the center of the ring u^1 .
- 45 Fig. 1 is a lever pivoted on a stud carried by the side bracket z^1 , the long arm of which is connected by a link 3 to the sleeve 2 fitted loose on the plunger rod v .
- 4 is a split nut, which can be secured in 50 any desired position on a screw-threaded portion of the rod v as may be required by various lengths of the nipple u .
- 5 is a spiral spring, which bears against the underside of the split nut 4, tending to 55 press it upward, and on the top of the gland x^1 , pressing the sleeve s and the nipple u downward.
- A spring z^2 connected to the short arm of the lever z , raises the long arm when the 60 trigger y is drawn back, and allows the spring 5 to raise the piercing rod to the position marked v^5 in Fig. 4, while the nipple u is still retained in the position shown in Fig. 4, by the downward pressure 65 of the spring 5, the runner 9 of the fork
- lever 7 resting on the lowest part of the incline of the cam 6. With the piercing rod and the nipple in the positions just above indicated, air can pass from the chamber s through the nipple, into the hole made in 70 the parison by the plunger, for the purpose of blowing out the metal to form the bottle.
- The method of working is as follows: During the gathering or filling of the parison mold, the latter is in an inverted position, and the plunger and nipple have the position shown in Fig. 4, the lever z being held in the position shown in Fig. 1 by the trigger or catch y . The ring mold also is closed, the levers h , i and i^1 being in the 75 position shown in Fig. 2, and the runner 9 resting against the bottom of the inclined cam 6. In machines of the turnover type as the head is swung around to bring the mechanism and parison mold to the front 80 of the machine, the parison mold is automatically opened, and the parison is rotated through 180 degrees, so that the neck end is uppermost. The hand lever 11 Fig. 1 is then drawn down, and through the connecting link 12 pulls down the rod v to pierce the parison, compressing the spring 5. The lever 11 and plunger v are then allowed to move upward to the original position, and by drawing back the trigger or catch y , to 85 move still farther, until stopped by the split nut 4 catching against the underside of the bridge piece or plate 13 a . The lower end of the rod v is in the position marked v^5 90 Fig. 4, and on turning on the compressed air tap, air passes through the nipple to blow out the bottle in the finishing mold, which has been substituted for the parison mold. When this has been done, the operating handle h is moved in the direction indicated by the arrow in Fig. 2 to open the 95 ring mold, at the same time moving around the cam 6, so as to raise the lower end of the nipple clear off the bottle neck or mouth. The finishing mold is then swung to one side 100 with the bottle inclosed. The hand lever h is then allowed to move back and the ring mold to close under the action of the spring p , and the hand lever 11 is then drawn down until the catch y engages in the notch 110 in the plate 1, whereby the plunger and nipple are drawn and held in the position 115 shown in Fig. 4. The head is then rotated through 180 degrees, and the two halves of the parison mold are automatically closed together and brought into position with respect to the ring mold, both being at the same time inverted ready for the next filling or gathering operation.
- The additional means for piercing the 120 metal of the neck while in the gathering or parison mold, when at the rear or gathering side of the machine, are illustrated in Fig. 6.
- 14 is part of the bed plate, and 15 the rear 125

side of the pedestal or pillar of the glass bottle blowing machine.

16 is a foot lever, the free end of which passes to the front of the machine, so that the lever can be depressed, by the operator from this, (the front), side of the machine.

17 is a short shaft, one end of which is carried by the bracket 18, and the other end by the bracket 19.

10 20 is a chain attached at its lower end to the foot lever, its upper end being attached at 22 to a curved plate 21 mounted on the far end of the shaft 17, so that when the foot lever is depressed this shaft is 15 partly rotated.

23 is a toothed sector mounted on the shaft 17 and gearing with the vertical tappet rod 24, carried in guides on the bracket 18; whereby the tappet rod is raised, and 20 comes in contact with the cross head 13, see Fig. 1, at the end of the plunger rod *v.* When at the rear side of the machine, the mechanism shown in Fig. 1 has an inverted position to that shown in Fig. 1, so that the crosshead 13 is now the lowest part of the 25 mechanism and immediately over the striking plate 25 carried at the upper end of the tappet rod 24. The lever 16 is raised by a spring at the front side of the machine, and 30 the tappet rod 24 drops by its own weight.

I am aware that it is not new to shape the interior of a mold according to the exterior shape of the article to be molded; also that it is not new to open the ring-mold at right angles to the body mold; also that it is not new to vary leverage according to the work required; and therefore I do not broadly claim devices embodying or effecting any of the above constructions or 40 operations; but—

Having now particularly described and ascertained the nature of my said invention and in what manner the same is to be performed, what I claim and desire to secure by Letters Patent is:

45 1. In a glass bottle blowing machine having sectional parison finishing and ring molds, a ring-mold in two sections, for forming the exterior of a bottle neck, and means 50 for supporting the latter mold and opening and closing it at will, the said sections of the ring-mold being divided in a plane at right angles to the plane of division of the parison and finishing mold sections and each section 55 of the ring-mold being provided with an integral interior projection, these two projections being opposite each other and adapted to form indentations, on a line transverse to the plane of division of said ring mold in the outside of 60 the bottle neck, for receiving and engaging the stopper-wire.

2. In glass-bottle blowing machines of the type herein referred to, the combination of two semi-annular sections adapted to be closed together, forming a ring-mold, each

section being provided with an integral projection from its inner face on a line transverse to the opening plane of said ring mold to form an indent in the bottle neck for holding a stopper wire, an operating lever 70 for opening and closing said mold sections, spindles arranged one on each side of the center of said mold, arms from said spindles to said mold-sections respectively and links connecting said lever to said spindles in order that both sections may be operated by one movement.

3. In glass bottle blowing machines of the type herein referred to, the combination of two semi-annular sections provided on their 80 inner faces with integral indent-forming projections on a line transverse to the plane of the opening of said ring mold and adapted to be closed together, forming a ring mold, and opened at will, an operating lever 85 pivoted in line with the center of said mold, a pair of spindles arranged respectively on each side of said central line, links from said lever to said spindles and arms of unequal length from said spindles to said sections for 90 the purpose set forth.

4. In combination with a ring-mold in two sections, a lever and connections by which said sections are opened and closed, a cam turning with said lever, a vertically movable sleeve carrying a nipple which is normally presented within said mold from above and an intermediate device actuated by said cam and engaging said sleeve to raise the latter and said nozzle substantially 95 as set forth.

5. In combination with a ring-mold in two sections, a lever and connections by which said sections are opened and closed, a cam turning with said lever, a pair of sleeves 100 vertically movable together but having screw-threaded connection for adjustment of their collective length, a nozzle carried by the inner of said sleeves and entering said ring-mold from above and an intermediate device actuated by said cam and engaging the outer sleeve of said pair to lift said nozzle out of said mold as the latter is opened.

6. In combination with a ring-mold in two sections, a lever and connections by which said sections are opened and closed, a tubular pillar on which said lever is mounted by means of a hub or sleeve at one end thereof, a cam carried by said hub or sleeve, 115 a hinged lever actuated by said cam, an adjusting sleeve arranged concentrically with in said pillar, engaged by said hinged lever for vertical movement and internally screw-threaded, an externally screw-threaded inner sleeve engaging said adjusting sleeve for adjusting the position of the nozzle, a spring tending to depress said sleeves, and a nozzle attached to the lower end of said inner sleeve, in order that it may be automati- 120 125 130

- cally introduced by the spring into said ring-mold when the latter closes and withdrawn when the ring-mold opens, also by the reverse motion of said lever.
8. 7. In combination with a sectional ring-mold, a lever and connections for opening and closing the same, a cam turned by said lever, a spring-depressed vertically movable sleeve provided with an annular groove or race, a nozzle-carrying sleeve depending from the first named sleeve and adjustable therein but spring depressed therewith provided at its upper end with a stuffing box and inlet for compressed air, a locknut for holding the latter sleeve in the position to which it may be adjusted, means for piercing the glass in the mold reciprocating through said stuffing box, sleeves and nozzle and a forked lever arranged to be actuated by said cam and provided with runners fitting in said groove, in order that the movements of the first mentioned lever in closing and opening said ring-mold may respectively permit said nozzle to enter said mold from above and may lift it out of said mold.
8. In a bottle molding machine, in combination with mechanism for operating the body mold and mechanism for operating the ring mold, a sectional body-mold and a sectional ring-mold for forming the neck, the plane of division of the latter being arranged at right angles to the plane of division of the former, the ring-mold sections opening respectively toward and away from the machine, and having projections arranged in the same plane with the division line of the body-mold and at right angles to the front of the machine, in order that the
- bottle-body may present a finless front on which the stopper clamping wire bail, pivoted in the indents formed by such projections, may fold down.
9. In combination with a ring-mold for forming a bottle-neck and consisting of sections which open respectively toward and away from the machine, a pair of arms operating said sections and arranged on opposite sides of the central vertical plane through said sections from front to rear, and means for forming a bottle-body with a finless front adapted to have words molded therein, the said ring-mold sections being provided with indent-forming projections arranged in the plane of division of the body-mold in order that the stopper-locking wire bail pivoted in said indents may fold down on the front of the body impressed with said words substantially as set forth.
10. In combination with a neck ring-mold in two sections for forming the neck of a bottle, arms for carrying said sections pivoted on opposite sides of a central vertical plane through said sections taken transversely to the line of division, the said sections being arranged to open respectively toward and from the machine, substantially as set forth.

In testimony whereof, I have signed my name to this specification in the presence of two subscribing witnesses.

ALBERT EDWARD CLEGG.
